[57] CLAIM

The ornamental design for a jewelry display stand, as shown and described.

DESCRIPTION

FIG. 1 is a top plan view of the bottom component of a jewelry display stand showing our new design;

FIG. 2 is a typical side elevational view;

FIG. 3 is a bottom plan view;

FIG. 4 is a sectional view taken along line 4—4 of FIG. 3;

FIG. 5 is a top plan view of the middle component of the jewelry display stand;

FIG. 6 is a typical side elevational view;

FIG. 7 is a bottom plan view;

FIG. 8 is a sectional view taken along line 8—8 of FIG. 7;

FIG. 9 is a top plan view of the top component of the jewelry display stand;

FIG. 10 is a typical side elevational view;

FIG. 11 is a bottom plan view;

FIG. 12 is a sectional view taken along line 12—12 of FIG. 11;

FIG. 13 is a top plan view of the jewelry display stand;

FIG. 14 is a typical side elevational view;

FIG. 15 is a sectional view taken along line 15—15 of FIG. 13;

FIG. 16 is a top plan view of the bottom component of a second embodiment of the jewelry display stand shown in FIG. 13;

FIG. 17 is a typical side elevational view;

FIG. 18 is a bottom plan view;

FIG. 19 is a sectional view along line 19—19 of FIG. 18;

FIG. 20 is a top plan view of the middle component of the second embodiment of the jewelry display stand;

FIG. 21 is a typical side elevational view;

FIG. 22 is a bottom plan view;

FIG. 23 is a sectional view taken along line 23—23 of FIG. 22;

FIG. 24 is a top plan view of the top component of the second embodiment of the jewelry display stand;

FIG. 25 is a typical side elevational view;

FIG. 26 is a bottom plan view;

FIG. 27 is a sectional view taken along line 27—27 of FIG. 26;

FIG. 28 is a top plan view of the second embodiment of the jewelry display stand;

FIG. 29 is a typical side elevational view; and,

FIG. 30 is a sectional view taken along line 30—30 of FIG. 27.

The three components have been shown separately in FIGS. 1-12 and 16-27 for convenience of illustration.
